Primary Examiner — John R Yeh(74) Attorney, Agent, or Firm — Withers & Keys, LLC(57) CLAIM

The ornamental design for a toy chest, as shown and described.

DESCRIPTION

FIG. 1 is a front, perspective view of a toy chest showing our new design;

FIG. 2 is a rear, perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof;

FIG. 8 is a bottom view thereof; and,

FIG. 9 is another front, perspective view of the toy chest with the mouth and seat sections shown in an open configuration.

The broken lines illustrate portions of the toy chest that form no part of the claimed design.
